UNITED STATES PATENT OFFICE.

JOHN H. ALLEN, OF BROOKLYN, NEW YORK.

BED-PLATE FOR ENGINES.

SPECIFICATION forming part of Letters Patent No. 236,661, dated January 18, 1881.

Application filed October 9, 1880. (No model.)

To all whom it may concern:

Be it known that I, JOHN H. ALLEN, of Brooklyn, State of New York, have invented certain new Improvements in Bed-Plates for 5 Steam-Engines, of which the following is a specification.

The nature of my invention consists in the arrangement and construction of the bed-plate, more particularly for high-speed engines, in 10 making the same throughout its whole length of a regular and even rectangular shape, with a straight top surface, inclosing nearly in height the whole of the crank or crank-wheel, whereby great solidity and strength is obtained, and 15 the scattering of the oil or other lubricating fluid is confined within the bed-plate.

In the accompanying drawings, Figure I represents a top view of my improved bed-plate. Fig. II is a side elevation of the same. 20 Fig. III is a section at line *a a*, Fig. I. Fig. IV is a cross-section near the center of shaft at line *b b*, Fig. I.

Similar letters represent similar parts in all the figures. 25 A represents the bed-plate, which, in its general shape, is made rectangular in section, of even dimension throughout its whole length, similar to a long rectangular box, with the pillow-block B cast in at one side. At that end 30 of the bed-plate where the steam-cylinder C is attached the inside of the bed-plate is made cylindrical to act as a guide for a cylindrical cross-head, E. The top of the bed-plate is carried above this cylindrical part D and continued in the same plane, perfectly straight 35

throughout the whole length, and is extended around the crank or crank-wheel F. From the end of the cylindrical part D toward the pillow-block the top of the frame or bed-plate is made open enough to permit the free movement of the connecting-rod and crank or crank-wheel. This construction of the cylindrical cross-head guide D in the inside of the bed-plate, and the straight top of the bed-plate above the guide D, and extending at the 40 same height throughout the whole length and nearly inclosing the crank or crank-wheel F, will prevent nearly all scattering of the lubricating-oil from the moving parts of the engine, and confine the same inside of the bed-plate, at the same time giving a strong and 45 solid bed-plate, capable of resisting effectually any strain, particularly requisite for high-speed engines.

What I claim as my invention, and desire to 50 secure by Letters Patent, is—

An engine bed-plate of rectangular section throughout its whole length, having a straight top surface above the cross-head guide extending at the same horizontal plane around 55 the crank or crank-wheel, in combination with an internal cross-head guide, D, consisting of a regular cylinder, all constructed and arranged substantially in the manner and for the purpose described.

JOHN H. ALLEN.
